UNITED STATES PATENT OFFICE.

CHARLES ORVILLE GRIMSLY, OF LOUISVILLE, KENTUCKY.

COIN-CONTROLLED FLUID-DISPENSER.

1,325,786.

Specification of Letters Patent. Patented Dec. 23, 1919.

Application filed July 3, 1919. Serial No. 303,401.

To all whom it may concern:

Be it known that I, CHARLES O. GRIMSLY, a citizen of the United States, residing in the city of Louisville, county of Jefferson, and State of Kentucky, have invented 5 a new and useful Improvement in Coin-Controlled Fluid-Dispensers, of which the following is a specification.

This invention relates to coin controlled 10 fluid dispensers, more particularly to that class adapted to be operated only after the deposit of a coin.

An object of this invention is to provide 15 a device of the character described which may be placed in parks or other places much frequented by the public, wherewith individuals may serve themselves.

A further object is to provide a device 20 as characterized which will be economical in construction, durable in service and efficient in operation.

With the foregoing and other objects in view, the invention consists of the novel construction and arrangement of parts illustrated in the accompanying drawings (comprising two sheets) which form a part of this specification, wherein is set forth an embodiment of the invention, but it is to be understood that such changes and modifications 30 may be resorted to as come within the scope of the claims appended hereunto.

In the drawings wherein similar reference characters designate like parts in the several views, Figure 1, is a front elevation of an embodiment of the invention, parts being broken away to show the construction; Fig. 2 a central vertical transverse section, on an enlarged scale; Fig. 3 a detached detail (on an enlarged scale) 40 partly in elevation and partly in section, of the operating mechanism; Fig. 4, a rear elevation (with parts omitted) of Fig. 3, and Fig. 5, a top plan view of the device.

The invention comprises a base —11—, 45 which may be set in the ground, the top being flush with the surface and a column —12— erected centrally thereon. The base is preferably rectangular and is constructed with the inner and outer walls —13, —14— which define a space which may be filled with a suitable non conductor of heat —15—. The column 12 is likewise constructed with double walls and the intervening space filled with an insulating medium. A tank —16—, for the reception of 50 a fluid to be dispensed, is disposed in the

base directly under the column, and may extend upward thereinto. The space on each side of the tank is for the reception of ice which may be placed therein by raising 60 hinged lids —17—. Vertical rods —18— serve to prevent the ice from contacting with and damaging the tank. A drainage pipe —19— provides an overflow. It will be observed that the chilled water has 65 free circulation all around the tank. A feed pipe —22— leads upward from a point near the bottom of the tank to a connection with a pump —23— at the rear end thereof. A delivery tube —24— leads from the pump 70 and terminates in a faucet —25— positioned exterior of the column in a recess, or alcove —26—, over a basin —27— from which a drain tube —28— leads. The pump is pivotally connected to the rear wall in 75 order to permit of a slight oscillatory movement incident to its operation. A short length of rubber hose, or tubing —29— is interposed in the continuity of the feed pipe, and another piece —30— in the delivery pipe, to permit of the oscillatory motion of the pump. A lever —31— is pivotally connected to a bracket —32— which is secured to the inner side of the front wall of the column just above the alcove. The 80 pump rod —35— is connected to a stud —36— near the outer end of the lever —31—. A bar —37— is slidably mounted on the inner side of the front wall just above the bracket 32. It is preferably angular in shape, and one leg —38— thereof overlies a slot —39— in the wall, the bar being held in position by means of a pin —40— the head —41— of which bears on the outer surface of the wall, and a handle 85 —42— near the lower end, a flange —43— of which bears on the outer surface of the wall. The handle furnishes means whereby the bar may be slid upward, and a spring —44— serves to return it to its normal position. An arm —45— is pivotally connected 100 respectively with the upper end of the bar 37, and with the lever 31. The arrangement being such that vertical rectilinear movement imparted to the bar 37 will through the 105 medium of the arm 45, draw back the lever 31, and with it the pump rod. The pump is so proportioned that at each full outward stroke of the pump rod, a given amount, say a half pint of fluid will be drawn into the 110 pump. As soon as the handle is released the spring tends to return the parts to their

normal position, forcing the fluid out of the pump but a check valve —46— prevents its return into the tank, and the faucet prevents its escape through the delivery pipe 5 until a valve lever —47— is depressed, when it may pass therethrough into a receptacle held under the faucet by a vendee. The lever 31, is provided on its inner, or free end with a notch —48— adapted for the 10 engagement therewith of a tooth, or projection —49— which extends from the lower end of a dog —50—. The dog is pivoted at a point —51— above and forward of its point of engagement with the lever, so that 15 it falls by gravity, the arrangement being such that the lever cannot be moved while the dog is in engagement therewith. A heel —52— of the dog contacts with a transverse bar —53— and limits the downward movement 20 of the dog. When the dog is in its normal position a lateral projection, or ear —54— thereon obstructs the exit from a coin chute —55— which extends inward and downward from a point on the exterior 25 of the front wall. When a coin is deposited in the chute it rolls downward therein until it is stopped by the ear of the dog. The bottom wall of the chute is cut away at —56—, at the lower end thereof to permit a 30 coin —57— which has been stopped by the dog, to drop therethrough on to the arm 45, which lies in the same vertical plane as the chute, and at that point is close thereto, and is provided with a concave depression —58— for the coin to rest in. The arm 35 is connected with the lever 31, by means of a slot —59— in the arm, which fits over a pin —60— projecting from a side of the lever, an interposed washer —61— spacing 40 them apart so that the lever will pass clear of the chute. The arrangement is such that when the bar is raised, an initial movement is imparted to the arm, the extent of which is limited by the length of the slot, before 45 it exerts traction on the lever. The object of the initial movement of the arm, is that it may, through the medium of the interposed coin, push the dog out of engagement with the lever, before it exerts a pull thereon. As soon as the dog is free of the lever, 50 the weight of the coin will raise it and the coin will roll into lower chute —62— which is suspended from the transverse bar 53, down which it falls into a till or box, 55 —63—, access to which may be had through a door —64— in a side wall. A door —65— affords means of access to the interior of the column for the purpose of refilling the tank.

It is thought that the foregoing description is sufficient to enable anyone skilled in the art pertaining thereto to make and use the same.

Having thus described it, what I claim is:

1. In a device as characterized, a frame, 60 dispensing means positioned therein, a lever

pivotedly connected with said frame and with said means, a reciprocable member, an arm pivotally connected with said member and with the lever, a detent normally engaged with said lever to prevent movement 70 thereof and means for interposing a token between said arm and said detent whereby an initial movement of the arm will release the detent.

2. In a device as characterized, opposed supports, a pump positioned therebetween and pivotally connected to one thereof, a lever pivotally connected to the other support, said pump comprising a barrel and an extended rod, the outer ends of said lever 80 and of the rods being pivotally connected, a member slidably associated with the second named support and an arm pivotally connected with said slidably member at the upper end thereof and with said lever at 85 the outer end thereof, the arrangement being such that vertical movement of the sliding member will draw out the pump rod, a detent normally engaged with the lever and means for interposing a coin between 90 said arm and the detent, whereby upon actuation of the sliding member initial movement of the arm, will through the medium of the interposed coin, disengage the locking element and permit continued movement 95 of the sliding member to move the lever.

3. In a device as characterized, opposed supports, a pump positioned therebetween and pivotally connected to one thereof, a lever pivotally connected to the other support, said pump comprising a barrel and an extended rod, the outer ends of said lever 100 and of the rod being pivotally connected, a member slidably associated with the second named support and an arm pivotally 105 connected with said slidably member at the upper end thereof and with said lever at the outer end thereof, the arrangement being such that vertical movement of the sliding member will draw out the pump rod. 110

4. A member slidably mounted on a fixed support, a lever disposed at an angle to said support and pivoted by one end thereto and movable in a plane parallel with said sliding member, an arm pivotally connected to the upper end of the sliding member and having a lost motion connected with the free end of the lever, a locking element adapted to be engaged with the lever, means for interposing a coin between said arm and the locking means, whereby upon actuation of the sliding member an initial movement of the arm, will through the medium of the interposed coin, disengage the locking element and permit continued movement of the 115 sliding member to move the lever. 120

5. A sliding member mounted upon a fixed support, a lever pivoted by one end to and extending upward at an angle from said support, said lever being capable of 125 130

movement in a plane parallel with the sliding member, an arm pivotally connected with the upper end of the sliding member and having a slot near the other end thereof engaged over a pin extended from the lever near its outer end, a dog engaged with the lever and adapted to prevent movement thereof, and means for interposing a coin between said arm near its connection with

the lever and the dog, the arrangement being such that upon actuation of the sliding member an initial movement of the arm will through the medium of the interposed coin push the dog out of engagement with the lever and permit of its actuation by the continued movement of the sliding member.

CHARLES ORVILLE GRIMSLEY.
